UNITED STATES PATENT AND TRADEMARK OFFICE
CERTIFICATE OF CORRECTION

PATENT NO. : Des. 326,637

DATED : June 2, 1992

INVENTOR(S) : Timothy J. Dietz

It is certified that error appears in the above-identified patent and that said Letters Patent is hereby corrected as shown below:

In the Description, "and," preceding "FIG. 3", should be deleted; in the last line, the period following "thereof" should be changed to a semicolon and the following should be inserted:

--FIG. 4 is a rear elevational view thereof;

FIG. 5 is a side elevational view thereof.--.

Signed and Sealed this

Eleventh Day of January, 1994
